ARTHUR R. HAVENER, OF WAYLAND, MASSACHUSETTS, ASSIGNOR TO JUDSON L. THOMSON MANUFACTURING CO., OF WALTHAM, MASSACHUSETTS, A CORPORATION OF MASSACHUSETTS.

RIVETING MACHINE.

Application filed April 12, 1924. Serial No. 706,103.

This invention relates to a riveting machine and has for its object to provide a mechanism of the class set forth in which pieces of sheet material may first be punched 5 and then riveted together.

Another object of the invention is to provide a machine embodying therein separate punching and rivet setting instrumentalities together with a mechanism for alternately 10 moving each of said instrumentalities into the same operative position relatively to the sheet material, the latter first having a hole punched therein by the punching instrumentalities which are then withdrawn, and with 15 the sheet material remaining in its initial position, the rivet setting instrumentalities are moved into alignment with said opening, after which a rivet is inserted therethrough and subsequently clinched.

Still another object of the invention is to 20 provide a riveting machine in which the rivet carrier is yieldingly supported upon the driver slide.

Other objects of the invention consist in 25 providing strong and simple combinations of mechanism whereby great speed and accuracy may be obtained to attain the objects hereinbefore set forth, all as will hereinafter appear in the specification and as set forth in 30 the claims.

The invention consists in the combination and arrangement of parts set forth in the following specification, and particularly pointed out in the claims.

Referring to the drawings:

Figure 1 is a plan view of a riveting machine embodying my invention.

Fig. 2 is a front elevation of the machine.

Fig. 3 is a left hand side elevation of the 40 same.

Fig. 4 is a horizontal section taken on the line 4—4 of Fig. 3.

Fig. 5 is a detail vertical section taken on the line 5—5 of Fig. 1 as viewed from the 45 rear of the machine.

Fig. 6 is a side elevation of a portion of the rivet feeding mechanism looking in the direction of the arrow *a* in Fig. 2.

Fig. 7 is a detail horizontal section of a 50 portion of the mechanism illustrated in Fig. 6, said section being taken on the line 7—7 of Fig. 2.

Fig. 8 is a front elevation of a portion of the punching and rivet setting mechanism,

the bearing plate being removed from the 55 front of the head and a portion of the mechanism being broken away and illustrated in section.

Fig. 9 is a detail vertical section taken on the line 9—9 of Fig. 8 looking in the direction of the arrows on said line.

Figs. 10 and 11 are detail sectional elevations illustrating the relative positions of the punching mechanism and stripping mechanism during the punching operation.

Figs. 12, 13, 14 and 15 are detail sectional elevations illustrating the relative positions of certain of the parts during the punching and riveting operations.

Figs. 16 and 17 are detail plan views illustrating the positions the die and anvil plate assume during the punching and riveting operations.

Fig. 18 is a side elevation of a portion of the riveting machine located adjacent to the 75 work support and illustrating a work clamping device attached thereto.

Like numerals refer to like parts throughout the several views of the drawings.

In the drawings, 20 is the frame of the 80 machine and 21 is the main driving shaft which is journaled to rotate in a suitable bearing 22 provided in said frame. The main driving shaft 21 has a pinion 23 fast thereon and meshing with a gear 24 which 85 is journaled to rotate upon a shaft 25, the latter being mounted in bearings 26 and 27 secured to said frame. The gear 24 constitutes one member of a clutch 28, another member 29 of which is rigidly fastened to 90 the shaft 25. The two members 24 and 29 of the clutch 28 are clutched together as one piece by suitable mechanism (not shown in the drawings, but well known to those skilled in the art), said mechanism being 95 operated from a suitable treadle (not shown) by a lever 30 and treadle rod 31.

The work, as for example, sheet material A which is to be operated upon is supported upon a work support 32 which is secured 100 at the outer end of an arm 33 formed integral with the frame 20. Mounted in the work support 32 is a block 34 embodying therein an opening 35 constituting a die, and an anvil 36. The block 34 is mounted to 105 slide in a horizontal plane in the work support 32 and receives its movement from mechanism hereinafter to be described.

Rivets 38 which are to be utilized in riveting the sheet material A together are placed in a hopper 39, a rotary member 40 of which is driven by a pulley 41 fast thereto and a belt 42 from a pulley 43 formed integral with the clutch member 29. The rivets 38 pass from the hopper 39 down a raceway 44 to a separator slide 45, the latter being operated by mechanism hereinafter to be described, to feed said rivets one by one to another raceway 46 down which they pass into a rivet carrier 47. The rivet carrier 47 is constructed in two parts 48 and 49 which are supported upon spring arms 50 and 51 respectively and the latter are, in turn, fastened to the opposite sides of a rivet carrier slide 52 by a bolt 53. The rivet carrier slide 52 is mounted to slide in the head portion 54 of a swinging auxiliary frame 55, together with a driver slide 56, a punch slide 57 and a stripper slide 58, all of which are adapted to be moved vertically within said head by mechanisms hereinafter to be described, all of said slides being held in said head by a bearing plate 59 which is secured to the front of said head.

The auxiliary frame 55 is rigidly fastened in any suitable manner to a vertical shaft 60 which is mounted to rock in bearings 61 and 62 formed integral with the frame 20. A rocking movement is imparted to the auxiliary frame 55 and shaft 60 by a lever 63 pivoted at 64 to the frame 20, one end of said lever 63 being operatively connected by a link 65 with said frame 55 while the other end of said lever 63 has a cam roll 66 journaled thercon, said cam roll projecting into a groove 67 formed in the periphery of a cam 68 fast to the shaft 25.

Before the rivets 38 can be inserted in the sheet material A it is first necessary to punch holes through said material. This is accomplished by mechanism as follows:—Rigidly secured at the lower end of the punch slide 57 is a punch holder 69 in which a punch 70 is secured by a screw 71 and said punch 70 co-operates with the die 35 of the block 34 during the downward movement of said punch slide and punches a hole through the material A in the usual well known manner. A vertical reciprocating movement is imparted to the punch slide 57 by a lever 72 pivoted at 73 upon the frame 20 and the front extremity 74 of said lever 72 is cylindrical in form and projects into a sliding block 75 which is mounted in a member 76 rigidly secured to the upper extremity of the punch slide 57. The rear extremity of the lever 72 is forked at 77 being provided with furcations 78 and 79 between which a cam roll 80 is rotatably mounted. Another cam roll 81 is mounted in alignment with the cam roll 80 upon the opposite side of the furcation 79 from that upon which the cam roll 80 is mounted, and

said cam roll 81 projects into a groove 82 formed in the side of a cam 83. The cam roll 80 bears against the periphery 84 of an auxiliary cam 85, said periphery of said last-named cam being adjacent to and aligning with the inner wall of the cam groove 82. The cams 83 and 84 form, in effect, a single cam and provide a construction which co-operates with the structure of the adjacent end of the lever 72 in forming a strong and powerful driving means for a punch slide.

The driver slide 56 has a driver 86 rigidly fastened thereto in any suitable manner and projecting downwardly from the lower end thereof and said driver slide has a vertical reciprocatory motion imparted thereto by a lever 87 pivoted at 88 upon the frame 20 and the front extremity 89 of said lever 87 is cylindrical in form and projects into a sliding block 90 which is mounted in a member 91 rigidly secured to the upper extremity of said driver slide 56. The rear extremity of the lever 87 is forked at 92 being provided with furcations 93 and 94 between which a cam roll 95 is rotatably mounted. Another cam roll 96 is mounted in alignment with the cam roll 95 upon the opposite side of the furcation 94 from that upon which the cam roll 95 is mounted, and said cam roll 96 projects into a groove 97 formed in the side of the cam 68 hereinbefore mentioned. The cam roll 95 bears against the periphery 98 of an auxiliary cam 99, said periphery of said last-named cam being adjacent to and aligning with the inner wall 100 of the cam groove 97. The cam groove 97 of the cam 68 and the auxiliary cam 99 form, in effect, a single cam, and provide a construction which co-operates with the structure of the adjacent end of the lever 87 in forming a strong and powerful driving means for the driver slide 56.

After a hole has been punched in the material A, and the punch has been withdrawn from the material, the frame 55 is rocked to move the punch out of alignment with said hole and the driver 86 into alignment therewith, and at the same time the block 34 is moved to position the anvil 36 beneath the hole in said material in order that a rivet may be clinched in the material after said rivet has been driven through the hole. The block 34 is therefore, moved to position the anvil 36 as above outlined by mechanism as follows:—Rigidly fastened in any suitable manner to the vertical rock shaft 60 is an arm 101 and the latter is operatively connected by a link 102 with a bell crank lever 103 pivotally mounted at 104 upon the frame 20. The bell crank lever 103 is, in turn, connected by an adjustable connecting rod 105 with a bracket 106 rigidly fastened to a slide 107 which is mounted to slide in a vertical plane between ways 108

provided in the arm 33 of the frame 20, as illustrated in Fig. 4. The block 34 is adjustably mounted in any suitable manner at the front end of the slide 107. The slide 107 is securely held in the arm 33 by a plate 109 which is detachably secured to the upper surface of said arm. It will, therefore, be seen that with each rocking movement imparted to the frame 55 by the cam 68 to move the driver 86 into position above the hole that has been punched in the sheet material, the block 34 will at the same time be moved to position the anvil 36 in alignment with said driver.

15 A column of rivets 38 in the raceway 44 are fed one by one to the raceway 46 by the slide 45 in a manner well known to those skilled in the art, said slide being driven by a yielding mechanism so as to avoid any injury to the rivet in case it should become jammed during its passage from one of said raceways to the other.

Referring particularly to Figs. 6 and 7, a member 110 is rigidly secured in any suitable manner to the head portion 54 of the swinging frame 55 and said member 110 has a pin 111 projecting therefrom which engages an arm 112 of a bell crank lever 113 pivoted at 114 to the frame 20. Another arm 115 of the bell crank lever 113 has a pin 116 projecting therefrom which engages a shoulder 117 formed upon the slide 45. A spring 118 connects the pin 116 with a pin 119 projecting from the frame 20 and said spring, therefore, always acts to hold the arm 112 of the bell crank lever 113 against the pin 111. Another spring 120 is connected at one end thereof to the pin 116, while the opposite end of said spring is connected to a pin 121 mounted in one end of the slide 45. This last mentioned spring always acts to hold the slide 45 in yielding engagement with the pin 116. With each rocking movement imparted to the frame 44, as the head portion 54 of said frame moves in the direction of the arrow *b*, Fig. 7, the pin 111 will engage the arm 112 of the bell crank lever 113 thereby rocking said lever and causing the spring 120 to pull the slide 45 toward the left in Fig. 6 always holding the shouldered portion 117 of said slide against the pin 116. This movement of the slide 45 carries the lowermost rivet 38 in the column of rivets in the raceway 44 into alignment with the raceway 46 down which said rivet passes into the rivet carrier 47. During the movement of the frame 55 in a reverse direction to that indicated by the arrow *b* in Fig. 7 the spring 118 will act to rock the bell crank lever 113 in an opposite direction to that previously mentioned holding the arm 112 thereof against the pin 111 and causing the pin 116 to force the slide 45 toward the right in Fig. 6 and back to its initial position.

The rivet carrier slide 52 is mounted as hereinbefore stated in the head portion 54 of the swinging frame 55 between the punch slide 57 and the driver slide 56 and is yieldingly mounted relatively to the latter and has a vertical reciprocating movement imparted thereto as follows:—Referring particularly to Figs. 8 and 9, the rivet carrier slide 52 is provided with a slot 122 extending longitudinally thereof for a portion of its length and said slide is also provided with a hole 123 extending from the upper extremity thereof and communicating with the slot 122. Grooves 124 are also provided in the opposite sides of the slot 122, said so grooves being extensions of the hole 123. A pin 125 projects from the side of the driver slide 56 located adjacent to the rivet carrier slide 52 into the slot 122 of the latter. A cylindrical member 126 is slidably mounted in the slot 122 and grooves 124 of the slide 52 and rests upon the pin 125 and said cylindrical member constitutes a seat against which the lower end of a spring 127 located within the hole 123 may rest, the upper end of said spring contacting with the lower extremity of an adjusting screw 128. An angle plate 129 is fastened at the upper end of the rivet carrier slide 52 and said plate engages the upper extremity of the bearing plate 59 and constitutes a stop to limit the downward movement of said rivet carrier slide 52.

As the driver slide 56 is moved downwardly by the mechanism hereinbefore described, the driver 86 contacts with a rivet 38 resting as illustrated in Figs. 12 and 13 in the rivet carrier 47 and simultaneously forces said rivet downwardly in said carrier and causes the rivet carrier slide 52 to move downwardly as illustrated in Fig. 14 until the stop 129 engages the upper extremity of the bearing plate 59. At this time the lower extremity of the rivet carrier 47 is located a short distance above the upper surface of the material A as illustrated in Fig. 15. After the driver 86 has forced the rivet 38 through the material A and against the anvil 36 causing said rivet to be clinched as illustrated in Fig. 15, as the driver slide 56 moves upwardly, the pin 125 carried by said driver slide 115 will compress the spring 127 and eventually cause the rivet carrier slide 52 to move upwardly to its initial position as illustrated in Fig. 8.

After the punch 70 has been forced through the material A, it is desirable that means shall be provided for removing said material from said punch during the upward movement of the latter. This mechanism hereinafter to be referred to as the stripping mechanism is as follows:—Referring particularly to Figs. 9, 10 and 11, the stripper slide 58 is provided at its lower end with a laterally projecting extension 130 upon the under side of which is located a frusto-coni-

cal work engaging portion 131. A hole 132 extends through the extension 130 and conical portion thereof and the punch 70 reciprocates through this hole. The slide 58 has a tooth 133 formed thereon which is engaged by a pawl 134 pivoted at 135 to the frame 55 and a spring 136 acts to normally force the lower end of said pawl against an edge of the stripper slide 58 and into engagement with said tooth 133 when said slide is located in its lowermost position. A pin 137 projects from the side of the pawl 134 and said pin is engaged by a cam 138 fast to the punch slide 57 during the upward movement of the latter, thereby disengaging said pawl from said tooth, and thereafter allowing the stripper slide 58 to be moved upwardly and out of engagement with the work by mechanism as follows:—

Referring particularly to Fig. 9, the stripper slide 58 is provided with a slot 139 extending longitudinally thereof for a portion of its length and said slide is also provided with a hole 140 extending from the upper extremity thereof and communicating with the slot 139. Grooves 141 are also provided in the opposite sides of the slot 139, said grooves being extensions of the hole 140. A pin 142 projects from the head 54 into the slot 139 and a cylindrical member 143 is slidably mounted in said slot 139 and grooves 141 and rests upon said pin 142 and said cylindrical member constitutes a seat against which the lower end of a spring 144 located within the hole 140 may rest, the upper end of said spring contacting with the lower extremity of an adjusting screw 145.

The spring 144 normally holds the upper surface of the extension 130 of the stripper slide 58 in engagement with the under surface of the punch holder 69. When, however, the punch slide 57 is forced downwardly, it will carry with it the stripper slide 58, carrying the latter from the position illustrated in Fig. 9 to that illustrated in Fig. 10, at which time the pawl 134 will drop over the tooth 133 but will be located a short distance thereabove. During the downward movement of the stripper slide 58, the spring 144 is compressed, and as soon as the punch slide 57 starts to move upwardly, the spring 144 will cause the stripper slide to move upwardly until the tooth 133 engages the lower end of the pawl 134, as illustrated in Fig. 11. The frusto-conical lower portion of the stripper slide 58 will now remain in engagement with the upper surface of the material A during the interval that the punch 70 is being withdrawn from said work and until the cam 138 engages the pin 137 when said pawl will be disengaged from said tooth allowing the spring 144 to again force the stripper slide 58 upwardly to its initial position.

The general operation of the mechanism

hereinbefore specifically described is as follows:—Assuming that two pieces of sheet material A which it is desired to rivet together, are placed upon the work support 32 and that that portion of the punching, stripping, rivet carrying and driving instrumentalities illustrated in Fig. 12 are positioned relatively to the work support 32 and the material A located thereon as illustrated in said Fig. 12; the operator starts the machine 70 by operating the clutch 28 in the usual well known manner. The punch slide 57 will then immediately start to descend, carrying with it the stripper slide 58 and said slides will continue to descend in unison until the lower extremity of the work engaging portion 131 of said stripper slide contacts with the work A and the punch 70 has been driven through said work. The punch slide 57 will then start to rise, leaving the stripper 85 in engagement with the work until the punch 70 has been removed from said work, as illustrated in Fig. 11, after which the stripper mechanism will also move upwardly to its initial position. 90

The swinging frame 55 is then rocked to align the driver 86 with the hole that has been punched in the work, and at the same time the block 34 is moved to align the anvil 36 with said hole in said work, the latter 95 remaining stationary upon the work support. The driver slide 56 now descends, carrying with it the driver 86 and the latter engages the rivet 38 which has previously been fed into position within the rivet carrier 47, and as said driver forces said rivet downwardly through the rivet carrier 47, as illustrated in Fig. 14, the rivet carrier slide 52 will also move downwardly in the head 54 of the swinging frame 55 and upon the driver slide 56 until the rivet carrier 47 assumes the position illustrated in Fig. 15. The rivet 38 upon being forced through the opening formed in the work will contact with the anvil 36 and will be clinched 100 against the under side of the work, as illustrated in Fig. 15. The driver slide 56 will then ascend carrying with it the rivet carrier slide 52 and rivet carrier 47 and as said slides return to their normal positions with 105 in the head 54 of the swinging frame 55, the latter will be rocked to its initial position as illustrated in Fig. 7, at which time the pin 111 will engage and rock the bell crank lever 113, causing the separator slide 115 45 to feed the lowermost rivet in the column of rivets in the raceway 44 into alignment with the raceway 46 and allowing said rivet to slide into position within the rivet carrier. The work A is then fed manually upon the 120 work support 32 and correctly positioned to receive another rivet and the sequence of operations previously mentioned is then repeated until all of the rivets necessary to 125 secure the layers of said material together 130

have been inserted therethrough and clinched therein.

- In certain classes of work it may be necessary to employ a device for clamping the work to the work support 32, and this may be accomplished by mechanism such as is illustrated in Fig. 18 in which a suitable clamping member 146 is illustrated as being pivotally mounted at 147 upon a bracket 148 pivotally mounted at 147 upon a bracket 148 10 located at the rear of the work support 32, and said clamping member 146 is held in yielding engagement with said work support, or the work located upon said work support, by a suitable spring 149.
- 15 When the clamping device is employed, the work is placed upon the work support 32 beneath the clamping member 146 and the latter holds said work firmly upon said work support during the various operations 20 hereinbefore set forth.

I claim:

1. A rivet setting machine comprising, in combination, rivet setting instrumentalities embodying therein a reciprocating driver 25 slide, a rivet carrier slide located adjacent to said driver slide, and provided with a slot therein, a rivet carrier mounted upon said rivet carrier slide, a member mounted upon said driver slide and projecting into said 30 slot, and a spring interposed between said member and said carrier slide and supporting the latter.

2. A machine for punching and riveting sheet material comprising, in combination, 35 punching instrumentalities embodying therein a punch and die, said punch being mounted to reciprocate in a direction perpendicular to said sheet material, rivet setting instrumentalities embodying therein a driver 40 and anvil, a cam, and means actuated by said cam to alternately move said punching instrumentalities and said rivet setting instrumentalities into the same operative position relatively to said sheet material.

- 45 3. A machine for punching and riveting sheet material comprising, in combination, punching instrumentalities embodying therein a punch and die, rivet setting instrumentalities embodying therein a driver and anvil, said driver being mounted to reciprocate in a direction parallel to its longitudinal median line to secure a rivet in said sheet material, a cam, and means actuated by said cam to alternately move said punching instrumentalities and said rivet setting instrumentalities into the same operative position relatively to said sheet material.

4. A machine for punching and riveting sheet material comprising, in combination, 60 punching instrumentalities embodying therein a punch and die; rivet setting instrumentalities embodying therein a driver and anvil, said punch and driver being mounted to reciprocate in a direction perpendicular to said sheet material, a cam, and means actu-

ated by said cam to move said punch and die into alignment with each other and said driver and anvil into alignment with each other.

5. A machine for punching and riveting 70 sheet material comprising, in combination, a block embodying therein a die and an anvil, a punch, a driver, said punch and driver each being mounted to reciprocate in a direction perpendicular to said sheet material, 75 a cam, and means actuated by said cam to alternately move said punch and driver into the same operative position relatively to said sheet material and to move said block to position said die and anvil to co-operate with 80 said punch and driver respectively.

6. A machine for punching and riveting sheet material comprising, in combination, 85 a work support, a block having sliding engagement with said work support and embodying therein a die and an anvil; a punch, a driver, a cam, and means actuated by said cam to alternately move said punch and driver into the same operative position relatively to said sheet material and to move 90 said block to position said die and anvil in alignment with said punch and driver respectively.

7. A machine for punching and riveting sheet material comprising, in combination, 95 a work support, a block having sliding engagement with said work support and embodying therein a die and an anvil; a punch, a driver, a cam, means actuated by said cam to alternately move said punch and driver 100 into the same operative position relatively to said sheet material and to move said block to position said die and anvil in alignment with said punch and driver respectively, means to move said punch into co-operative 105 relation with said die to punch a hole in said sheet material, and means to move said driver to force a rivet through said hole and clinch the same to said material.

8. A machine for punching and riveting 110 sheet material comprising, in combination, punching instrumentalities, rivet setting instrumentalities embodying therein a reciprocating driver slide, a rivet carrier slide 115 located adjacent to said driver slide and provided with a slot therein, a rivet carrier mounted upon said rivet carrier slide, a member mounted upon said driver slide and projecting into said slot, a spring interposed 120 between said member and said carrier slide and supporting the latter, and means to alternately move said punching instrumentalities and said rivet setting instrumentalities into the same operative position relatively to said sheet material.

9. A machine for punching and riveting 125 sheet material comprising, in combination, punching instrumentalities embodying therein a punch and die, rivet setting instrumentalities embodying therein a driver slide, 130

driver, and anvil, a rivet carrier yieldingly mounted upon said driver slide, a cam, and means actuated by said cam to alternately move said punching instrumentalities and 5 said rivet setting instrumentalities into the same operative position relatively to said sheet material.

10. A machine for punching and riveting sheet material comprising, in combination, 10 punching instrumentalities, punch stripping instrumentalities yieldingly mounted relatively to said punching instrumentalities, rivet setting instrumentalities embodying therein a reciprocating driver slide, a rivet 15 carrier slide located adjacent to said driver slide and provided with a slot therein, a rivet carrier mounted upon said rivet carrier slide, a member mounted upon said driver slide and projecting into said slot, a spring interposed between said member and 20 said carrier slide and supporting the latter, and means to alternately move said punching and punch stripping instrumentalities jointly and said rivet carrier and rivet setting instrumentalities jointly into the same 25 operative position relatively to said sheet material.

11. A machine for punching and riveting sheet material comprising, in combination, 30 punching instrumentalities embodying therein a punch, means to strip sheet material from said punch, a pawl to hold said stripping means in engagement with said sheet material while said punch is being 35 withdrawn therefrom, means to actuate said pawl to release said stripping means from engagement with said material, rivet setting instrumentalities embodying therein a driver slide, a rivet carrier yieldingly mounted up- 40 on said driver slide, means to feed rivets into said rivet carrier, and means to alternately move said punching and punch stripping instrumentalities jointly, and said rivet carrier and rivet setting instrumentalities 45 jointly, into the same operative position relatively to said sheet material.

12. A machine for punching and riveting sheet material comprising, in combination, a stationary work support, a block mounted 50 to slide in a horizontal plane in said work support and embodying therein a die and anvil, a punch, means to force said punch into and out of engagement with material upon said work support whereby a hole is 55 formed therein, a driver, a cam, means actuated by said cam to simultaneously move said block and driver to position the latter together with said anvil in alignment with said hole in said material, and means to 60 move said driver to insert a rivet through said hole and clinch the same in said material.

13. A machine for punching and riveting sheet material comprising, in combination,

a main frame, an auxiliary frame pivotally mounted upon said main frame, punching instrumentalities embodying therein a punch and die, said punch being mounted in said auxiliary frame, rivet setting instrumentalities embodying therein a driver and anvil, 65 said driver being mounted in said auxiliary frame, a cam, and means actuated by said cam to rock said auxiliary frame to alternately move said punching instrumentalities and said rivet setting instrumentalities into 70 the same operative position relatively to said sheet material.

14. A machine for punching and riveting sheet material comprising, in combination, 80 a main frame, an auxiliary frame pivotally mounted upon said main frame, punching instrumentalities embodying therein a punch and die, said punch being mounted in said auxiliary frame, punch stripping instrumentalities mounted in said auxiliary frame, 85 rivet setting instrumentalities embodying therein a driver and anvil, said driver being mounted in said auxiliary frame, a cam, and means actuated by said cam to rock said auxiliary frame to alternately move said punching instrumentalities and said rivet setting instrumentalities into the same 90 operative position relatively to said sheet material.

15. A machine for punching and riveting sheet material comprising, in combination, 95 a main frame, an auxiliary frame pivotally mounted upon said main frame, punching instrumentalities embodying therein a punch, said punch being mounted in said auxiliary frame, punch stripping instrumentalities mounted in said auxiliary frame and operatively connected to said punching instrumentalities, means to release said stripping instrumentalities from engagement 100 with said sheet material, and means to rock said auxiliary frame to alternately move said punching instrumentalities and said rivet setting instrumentalities into the same 105 operative position relative to said sheet material.

16. A machine for punching and riveting sheet material comprising, in combination, 115 a main frame, an auxiliary frame pivotally mounted upon said main frame, punching instrumentalities embodying therein a punch, said punch being mounted in said auxiliary frame, punch stripping instrumentalities mounted in said auxiliary frame and operatively connected to said punching instrumentalities, means to release said stripping instrumentalities from engagement 120 with said sheet material, rivet setting instrumentalities embodying therein a driver slide and driver mounted in said auxiliary frame, a rivet carrier mounted upon said driver slide, and means to rock said auxiliary frame 125 to alternately move said punching instru-

mentalities and said rivet setting instrumentalities into the same operative position relatively to said sheet material.

17. A machine for punching and riveting sheet material comprising, in combination, a main frame, an auxiliary frame pivotally mounted upon said main frame, punching instrumentalities embodying therein a punch, said punch being mounted in said auxiliary frame, punch stripping instrumentalities mounted in said auxiliary frame and operatively connected to said punching instrumentalities, means to release said stripping instrumentalities from engagement with said sheet material, rivet setting instrumentalities embodying therein a driver slide and driver mounted in said auxiliary frame, a rivet carrier mounted upon said driver slide, means actuated by the movement of said auxiliary frame to feed rivets into said rivet carrier, and means to rock said auxiliary frame to alternately move said punching instrumentalities and said rivet setting instrumentalities into the same operative position relatively to said sheet material.

18. A machine for punching and riveting sheet material comprising, in combination, a main frame, an auxiliary frame pivotally mounted upon said main frame, punching instrumentalities embodying therein a punch, said punch being mounted in said auxiliary frame, a stripper slide mounted in said auxiliary frame and operatively connected to said punching instrumentalities, a pawl to hold said stripper slide in engagement with said sheet material, means to engage said pawl to disengage the latter from said stripper slide whereby the latter is released from engagement with said sheet material, rivet setting instrumentalities embodying therein a driver slide and driver mounted in said auxiliary slide, a rivet carrier mounted upon said driver slide, and means to rock said auxiliary frame to alternately move said punching instrumentalities and said rivet setting instrumentalities into the same operative position relatively to said sheet material.

19. A machine for punching and riveting sheet material comprising, in combination, a main frame, an auxiliary frame pivotally mounted upon said main frame, a work support, a block mounted to slide in a horizontal plane in said work support and embodying therein a die and anvil, a punch slide mounted in said auxiliary frame, a punch mounted in said punch slide, a lever operatively connected to said punch slide, a shaft, a cam fast to said shaft adapted to rock said lever whereby a reciprocating motion is imparted to said punch slide and a hole is punched in said material, a driver, means to simultaneously move said block and driver to position the latter together with said anvil in align-

ment with said hole in said material, and means to move said driver to insert a rivet through said hole and against said anvil thereby clinching said rivet in said material.

20. A machine for punching and riveting sheet material comprising, in combination, a main frame, an auxiliary frame pivotally mounted upon said main frame, a work support, a block mounted to slide in a horizontal plane in said work support and embodying therein a die and anvil, a punch slide mounted in said auxiliary frame, a punch mounted in said punch slide, a lever operatively connected to said punch slide, a shaft, a cam fast to said shaft adapted to rock said lever whereby a reciprocating motion is imparted to said punch slide and a hole is punched in said material, a driver slide mounted in said auxiliary frame, a driver mounted in said driver slide, means to simultaneously move said block and driver slide to position said driver together with said anvil in alignment with said hole in said material, a lever operatively connected to said driver slide, and another cam fast to said shaft and adapted to rock said last-named lever whereby a reciprocating motion is imparted to said driver slide and driver to insert a rivet through said opening and against said anvil thereby clinching said rivet in said material.

21. A machine for punching and riveting sheet material comprising, in combination, a main frame, a rock shaft mounted upon said main frame, an auxiliary frame fast to said rock shaft, a punch mounted upon said auxiliary frame, a driver mounted upon said auxiliary frame, a block mounted in said main frame and embodying therein a die and anvil, means operatively connecting said block with said rock shaft, and means to rock said auxiliary frame to alternately move said punch and driver into the same operative position relatively to said sheet material and to impart a reciprocatory movement to said block to position said die and anvil in alignment with said punch and driver respectively.

22. A machine for punching and riveting sheet material comprising, in combination, a main frame, a rock shaft mounted upon said main frame, an auxiliary frame fast to said rock shaft, a work support, a block mounted to slide in said work support and embodying therein a die and anvil, means operatively connecting said block with said rock shaft, a punch slide mounted in said auxiliary frame, a punch mounted in said punch slide, a lever operatively connected to said punch slide, a cam shaft, a cam fast to said cam shaft and adapted to rock said lever whereby a reciprocating motion is imparted to said punch slide and a hole is punched in said material, a driver mounted upon said auxiliary frame, and means to rock said auxiliary frame to alternately move said punch and driver into

the same operative position relatively to said sheet material and to move said block to position said die and anvil in alignment with said punch and driver respectively.

23. A machine for punching and riveting sheet material comprising, in combination, a main frame, a rock shaft mounted upon said main frame, an auxiliary frame fast to said rock shaft, a work support, a block mounted to slide in said work support and embodying therein a die and anvil, means operatively connecting said block with said rock shaft, a punch slide mounted in said auxiliary frame, a punch mounted in said punch slide, a lever operatively connected to said punch slide, a cam shaft, a cam fast to said cam shaft and adapted to rock said lever whereby a reciprocating motion is imparted to said punch slide and a hole is

punched in said material, a driver slide 20 mounted upon said auxiliary frame, a driver mounted in said driver slide, means to rock said auxiliary frame to alternately move said punch and driver into the same operative position relatively to said sheet material and to move said block to position said die and anvil in alignment with said punch and driver respectively, a lever operatively connected to said driver slide, and another cam fast to said cam shaft and adapted to 25 rock said last-named lever whereby a reciprocating motion is imparted to said driver slide and driver to insert a rivet through said hole and against said anvil, thereby clinching said rivet in said material.

30 In testimony whereof I have hereunto set my hand.

35 ARTHUR R. HAVENER.
